FRANK N. REEVES, OF NEWARK, NEW JERSEY, ASSIGNOR TO WESTERN ELECTRIC COMPANY, INCORPORATED, OF NEW YORK, N. Y., A CORPORATION OF NEW YORK.

ELECTRIC SIGNALING SYSTEM.

1,337,482.

Specification of Letters Patent.

Patented Apr. 20, 1920.

Continuation of application Serial No. 127,659, filed October 25, 1916. This application filed November 3, 1917. Serial No. 200,058.

To all whom it may concern:

Be it known that I, FRANK N. REEVES, a citizen of the United States, residing at Newark, in the county of Essex and State 5 of New Jersey, have invented certain new and useful Improvements in Electric Signaling Systems, of which the following is a full, clear, concise, and exact description.

This invention relates to electric signaling systems, and more particularly to a signaling system employed in automatic telephone exchanges. This application is a continuation of my application Serial No. 127,659, filed October 25, 1916.

15 It is the object of the present invention to provide a new and improved signaling arrangement in which the amount of apparatus needed for transmitting signals between two points, such as two operators' 20 positions, is reduced to a minimum.

According to the main feature of the present invention, a group of variably operable signals, such as lamps provided at one point, may be selectively associated with a 25 controlling station.

In the drawings Figure 1 represents as much of a controlling operator's position as is necessary for a clear understanding of the invention; Fig. 2, to be placed above 30 Fig. 1, represents the arrangement of a trunk finding switch by means of which the operator's controlling circuit may be extended to indicator switches arranged to actuate the signals; Fig. 3, to be placed above 35 Fig. 2, represents a plurality of variably operable number indicator switches of the sequence switch type, adapted to be set under the control of the operator, and signals controlled by these switches.

40 A sequence switch 100 shown in Fig. 1, controls contacts 101, 102, 103, 104, 105, 106 and 107. These contacts are closed only in such positions of the sequence switch as are indicated adjacent the respective contacts.

45 A master contact 108 of the sequence switch is closed in all positions, except the positions indicated adjacent thereto. This sequence switch and the other sequence switches used in the present system, 50 may be of the same structure as described in Patent No. 1,127,808 to J. N. Reynolds and C. F. Baldwin issued Feb. 9, 1915.

A sender shown within the dotted rec-

tangle in Fig. 1, is arranged in accordance with the sender fully described in Patent 55 No. 1,168,319 to A. E. Lundell issued Jan. 18, 1916. Contacts 109 and 110 are controlled by a sequence switch (not shown) associated with this sender. A relay contact 111 is opened under the control of the so-called upper zero counting relay. The number of operations to be performed by the counting relays until the energization of the upper zero counting relay occurs, is predetermined by the adjustment of the 60 sender; and the successive actuation of the predetermined number of counting relays is controlled by a stepping relay 112.

The sequence switch contacts shown in the lower left-hand part of Fig. 1 are partly 70 controlled by a sequence switch 100' and a sender sequence switch. All the other sequence switch contacts shown in Fig. 1 are controlled by a sequence switch 113. The sequence switches 113 and 100, by means 75 of their contacts, control the operation of a selector switch 116. The sequence switch 100', and another sequence switch (corresponding to 113) control the operation of a selector switch 116'. In view of the 80 fact that the operation of sequence switches 100 and 113 and selector 116 is similar to the operation of sequence switch 100' and the sequence switch corresponding to 113, only that of sequence switches 113 and 100 85 and selector 116 will be described in detail. It will be obvious from a study of the above Patent No. 1,168,319, that either one of the senders shown in Fig. 1 may be associated with either one of the selector switches. 90

An allotter 200 (Fig. 2) is of the same structure as the sequence switches used in this system and controls the contacts shown within the dotted rectangle around such allotter. Under the control of the allotter 200, 95 trunk finder 201 is preselected for service. The trunk finder may be of the same structure as the cord finder fully described in patent No. 1,168,319 to Lundell, Jan. 18, 1916, or the switch structure disclosed in 100 patent No. 1,123,696 to Craft and Reynolds, Jan. 5, 1915. The allotter 200 preselects the trunk finder 201 by moving a sequence switch 203, associated with such trunk finder, out of position 18 and into position 1. 105 The allotter has no normal position and will

accomplish this preselecting operation when in position 1. When the allotter is in position 4, into which position it is moved after the trunk finder associated with sequence 5 switch 203 has been taken into use, it will preselect for use a trunk finder associated with sequence switch 203', if such sequence switch was standing in position 18; that is to say, was awaiting preselection. The operation 10 of sequence switches 203 and 203' and of the trunk finders associated with such sequence switches is identical, and for this reason, only the operation of sequence switch 203 and trunk finder 201 is disclosed in detail 15 herein. Only so much is shown of the circuits of sequence switch 203' as is necessary for a full understanding of the present invention. The trunk finder 201 and the trunk finder associated with the sequence 20 switch 203' may seize, under the control of their associated sequence switches, any one of a plurality of trunks seized by selector 116 or selector 116'. The drawings show only means for permitting trunk finder 201 25 to select and seize a trunk seized by selector 116, as it is believed to be obvious how trunk finder 201 may be caused to select another trunk selected by selector 116, or any one of a plurality of trunks seized by selector 116', or how the trunk finder associated with sequence switch 203' may be caused to seize any one of the trunks selectable by trunk 30 finder 201.

An allotter 202 of the same type as the sequence 35 switches used in this system, controls the contacts shown within the dotted rectangle around this allotter.

In addition to the above mentioned function of sequence switch 203, this sequence 40 switch controls also the operation of indicators 301, 302, 303, 304 and 305 (Fig. 3). These indicators may be set in response to the adjustment of the sender, in accordance with the numerical designation of a called 45 line. The indicators are permanently associated with the trunk finder 201, and are thus connected to the sender. Each indicator controls the contacts shown above and below its power magnet with certain exceptions to be noted later. The contact shown 50 directly above each power magnet is the master contact controlling the stopping of the respective indicators in the positions noted adjacent such contacts.

Each of the indicators 300, 302, 303 and 55 304 may control, by means of its contacts, the variable operation of a set of lamps like 348. Depending upon the setting of the indicators, a certain number of lamps are 60 lighted to display any one of the numerals 0 to 9 (both inclusive), and thus indicate the number of the called subscriber's line to the operator who controls the completion of the desired connection. Such operator is usually 65 known as a "B" operator.

In the same manner as sequence switch 203, sequence switch 203' controls the operation of a set of indicators similar to those shown in Fig. 3. The circuits and mechanisms of such indicators are not disclosed, 70 because it would involve only a repetition of the matter shown in Fig. 3 and of the detailed description of this showing. Within a dotted rectangle in the upper left-hand part of Fig. 3 there are shown contacts 75 controllable by indicators similar to 300 and 301, which are in turn controlled by the sequence switch 203'.

Each set of lamps 348 is provided in common to the corresponding indicators controlled by sequence switches 203 and 203', and may obviously be made common to more than two corresponding indicators.

It will be seen from the above that both sets of indicators (those associated with sequence switch 203 and those associated with sequence switch 203') may be simultaneously controlled to actuate the lamps 348 to display a numeral. This may result in the sending of a false signal to the "B" operator, and, for this reason, means are provided in the form of the allotter 202 for determining the succession in which the operation of the indicators should become effective. As will be apparent from the detailed 90 description of the operation of the system, when allotter 202 is in position 1, the indicators associated with sequence switch 203 are permitted to cause the lighting of the lamps 348, and when this allotter is in position 4, the indicators associated with sequence switch 203' will be permitted to perform this function. Means are also provided for preventing the allotter 202 from moving out of position 1 and into position 4 100 until the indicators associated with sequence switch 203 have successfully completed their operation.

The invention will be more readily understood from the following detailed description 110 of a telephone system, in which a connecting or "A" operator conveys a visual signal to a "B" operator, and the appended claims.

As soon as a connecting operator receives 115 a call through a trunk 114, and ascertains the number of the subscriber wanted, she depresses an assignment key 115, closing a circuit from the plus pole of battery through the contact of this key, the contact 102 and 120 the power magnet of sequence switch 100, to the minus pole of battery. Under the control of its master contact 108, the sequence switch is moved into position 11. The operator then adjusts the sender which has 125 been connected to the trunk 114 in a manner described in the mentioned Patent No. 1,168,319, for controlling the setting of a selector 116 onto a trunk leading to the office 130 to which the called subscriber is connected,

and the setting of the indicators in accordance with the number of the called subscriber. While the sequence switch 100 is moving from position 1 into position 11, the 5 selector switch 116 is operated. Patent No. 1,168,319 contains a complete disclosure of the operation of selector switches such as 116, and for this reason no attempt will be made in the present description to further 10 dwell on the operation of this selector. It will be assumed that the selector has been successfully set onto the desired terminals, such as 117, 118. A fundamental circuit 15 is closed thereupon from the plus pole of battery, through a sequence switch contact 119, a resistance 120, terminal 118, selector wiper 121, sequence switch contact 104, sender sequence switch contact 109, the relay contact 111, the winding of relay 112, sequence switch contact 105, wiper 137, terminal 117, conductor 156, resistance 121', sequence switch contact 122, the winding of a relay 123, and sequence switch contact 124, to the minus pole of battery. Relays 112 20 and 123 become energized. Relay 123 closes a circuit from the plus pole of battery through its right-hand armature and front contact, a contact 125 and the power magnet of sequence switch 113, to the minus pole of 25 battery. Under the control of its master contact 126, the sequence switch is moved into position 2. A circuit is now closed from the plus pole of battery through sequence switch contact 127, conductor 128, sequence switch 30 contacts 204, 205, a conductor 206 and the winding of a relay 207 to the minus pole of battery. Relay 207 becomes energized and closes a circuit from the plus pole of battery, through its right-hand armature and 35 front contact, conductor 208, a contact 209 and the power magnet of sequence switch 203 to the minus pole of battery. Under the control of its master contact 210, the sequence switch is moved out of position 1 40 into position 2. The positions in which contact 210 is open are indicated adjacent to a master contact 210' of sequence switch 203'. When sequence switch 203 passes through position 1₁, the above traced circuit for relay 207 is replaced by a circuit 45 extending from the minus pole of battery, through the winding of this relay, conductor 206, sequence switch contacts 205 and 219, and the back contact and armature of relay 50 218 to the plus pole of battery. In position 2 of the sequence switch 203, a magnet 211 becomes energized by a circuit extending from the minus pole of battery, through the winding of this magnet, a sequence 55 switch contact 212, a conductor 208 and the right-hand front contact and armature 207 to the plus pole of battery. Under the control of magnet 211, the wipers of the 60 trunk finder switch 201 are caused to move in an upward direction over a bank of terminals containing one set of contacts for each trunk to which the selector 116 has access. The terminals shown in Fig. 2 are individual to the trunk terminating in selector contacts 117 and 118. Upon the engagement of this set of terminals; that is to say, upon the engagement of a set of terminals individual to a trunk, the sequence switch 113 associated with which is in position 2, a circuit is closed from the plus pole 65 of battery, through sequence switch contact 129, conductor 130, terminal 291, wiper 292, conductor 293, sequence switch contacts 213 and 214, conductor 215, sequence switch contacts 216 and 217, and the winding of a relay 218, to the minus pole of battery. Relay 218 by attracting its armature, closes a locking circuit for itself through sequence switch contacts 216 and 217, and by opening its back contact, opens the circuit of relay 207. In order to insure the proper centering of the trunk finder wipers on the terminals selected, whenever these wipers rest below or above a certain terminal, a circuit is closed from the plus pole of 70 battery, through a brush 220 moved in an upward direction, together with the wipers of the trunk finder, a conducting segment 221 adapted to be engaged by this brush, conductor 222, sequence switch contact 223, conductor 224, the left-hand armature, front contact and the winding of relay 207, to the minus pole of battery. As soon as the trunk finder wipers are exactly centered on the selected set of terminals, the brush 220 75 engages one of the insulated segments 225, and therefore, upon the energization of relay 218, relay 207 becomes deenergized and closes a circuit from the plus pole of battery through its right-hand armature and 80 back contact, a contact 226 and the power magnet of sequence switch 203 to the minus pole of battery, for moving this sequence switch out of position 2 into position 3. 85 In position 3 of sequence switch 203, a circuit is closed from the plus pole of battery through the armature and front contact of relay 218, sequence switch contacts 216 and 227, conductor 228, wiper 294, terminal 295, conductor 163, a contact 131 and 90 the power magnet of sequence switch 113, to the minus pole of battery, for moving sequence switch 113 out of position 2 and into position 3. Sequence switch contact 122 is now open, but relay 123 remains energized, a circuit being closed from the minus pole of battery, through sequence switch contact 124, the winding of relay 123, sequence switch contact 124, the left-hand armature and front contact of relay 125 123, sequence switch contacts 135 and 136, and then through the above traced fundamental circuit. In position 3 of sequence switch 113, a circuit is closed for again energizing relay 207. This circuit may be 130

traced from the minus pole of battery, through the winding of relay 207, sequence switch contacts 205 and 229, conductor 230, wiper 296, terminal 297, conductor 164, sequence switch contacts 132 and 133, and the right-hand front contact and armature of relay 123 to the plus pole of battery. Upon the energization of relay 207, a circuit is closed from the plus pole of battery, through the right-hand armature and front contact of this relay, conductor 208, and sequence switch contacts 209 and 235, and the power magnet of sequence switch 203, to the minus pole of battery, for moving this sequence switch out of position 3 and into position 4.

Assuming that the allotter 200 is in position 1, a circuit will now be closed from ground, through allotter contact 236, sequence switch contacts 237 and 238, a contact 239 and the power magnet of allotter 200, to grounded battery. Under the control of its master contact 240 the allotter is moved out of position 1 into position 4, in which position it controls the preselection of a sequence switch 203', and thus a trunk finder similar to 201 with which such sequence switch is associated. If sequence switch 203' is standing in position 18, a circuit is closed from grounded battery, through the power magnet and contacts 235' and 237' of sequence switch 203', and contact 236' of allotter 200 to ground. Under the control of its master contact 210', sequence switch 203' is moved into position 1, in which position relay 207' may be energized in the same manner as relay 207, for moving the sequence switch 203' out of position 1 and into position 2. The circuit extends from the minus pole of battery, through the power magnet and contacts 235', 209' of sequence switch 203', and the right-hand front contact and armature of relay 207' to the plus pole of battery. In position 2 of sequence switch 203', the trunk finder served by the sequence switch is started to hunt for the trunk assigned by the connecting operator.

A circuit is now closed from the minus pole of battery, through sequence switch contact 124, the winding of relay 123, sequence switch contacts 134, 165 and 166, conductor 167, terminal 298, wiper 299, conductor 299', sequence switch contact 298', conductor 297', conductor 369, normally closed contacts 370, 371, 372, 373, 374, 375 and 376 of the indicators 300 to 305, respectively, conductor 245, wiper 296', terminal 295', conductor 141, sequence switch contacts 140 and 136, and through the fundamental circuit to the plus pole of battery at sequence switch contact 119. Due to the closure of this circuit, if the relay 123 failed to lock up in the above described manner, it will now become energized and will close its locking circuit.

In position 4 of sequence switch 203, the number indicator 300 is operated. The circuit for this indicator extends from the minus pole of battery through the power magnet of the number indicator 300, conductor 306, sequence switch contact 241, conductor 224, the left-hand armature and front contact of relay 207, conductor 206, sequence switch contacts 205 and 229, conductor 280, wiper 296, terminal 297, conductor 164, sequence switch contacts 132 and 133 and the right-hand front contact and armature of relay 123 to the plus pole of battery. The indicator is moved under the control of its master contact from position 80 to position. While moving from one position to the next, that is to say, between positions N and X, positions X and 0, positions 0 and 1, etc., a contact 310 is closed. In response to each closure of contact 310, a shunt circuit is closed for relay 123, which circuit extends from the minus pole of battery through sequence switch contact 124, the winding of relay 123, sequence switch contact 134, the left-hand armature and front contact of relay 123, sequence switch contacts 135 and 140, conductor 141, terminal 295', wiper 296', conductor 245, conductor 311, contact 310, conductor 313, sequence switch contact 246 and the right-hand front contact and armature of relay 207, to the plus pole of battery. Due to the closure of this shunt circuit through the winding of relay 123, the stepping relay 112 at the sender becomes deenergized and starts the successive operation of the counting relays. After the indicator 300 takes a number of steps predetermined by the setting of the sender, which fact is indicated to the sender by the number of closures of contact 310, the upper zero counting relay (not shown) becomes energized and opens at contact 111 the fundamental circuit. The counting relays will be unlocked because sequence switch contact 109 is opened and relay 112 becomes deenergized. Relay 123 becomes also energized and causes relay 207 to release its armatures.

As soon as the indicator 300 reached position X a circuit was closed for the sequence switch 203 from the minus pole of battery through the power magnet of this sequence switch, sequence switch contact 247, conductor 248, indicator contact 314, the normally closed contacts 315^a, 316, 317, 318 and 319 of the other indicators respectively, conductor 320, sequence switch contact 248', conductor 249, and as soon as relay 207 becomes deenergized, through the back contact and right-hand armature of this relay to the plus pole of battery. The sequence switch 203 is thus moved into position 5 upon the opening of the fundamental circuit.

In the meantime, the fundamental circuit 130

is again closed, resulting in the energization of relays 112 and 123, and the latter causes the operation of relay 207. The circuit of relay 123 may be traced as follows: 5 minus pole of battery, 124, 123, 134, 165, 166, 167, 298, 299, 299', 294', 377, 378, 371, 372, 373, 374, 375, 376, 245, 296', 295', 141, 140, 136 and then through the fundamental circuit to the plus pole of battery. The plus 10 battery at the right-hand armature of relay 123, which was connected through the left-hand armature and front contact of relay 207 to the power magnet of indicator 300 in position 4 of sequence switch 203, is now connected through conductor 224, sequence switch contact 250, conductor 251, and the power magnet of the indicator 301 to the minus pole of battery. This indicator begins to rotate now and controls 15 20 in its contact 315 the operation of the stepping relay 112, and thus that of the counting relays. When the upper zero counting relay again becomes energized, relays 112 and 123 again become deenergized, and the latter causes the deenergization of 25 relay 207. When the relay 207 becomes deenergized, the sequence switch 203 is moved out of position 5 and into position 6, the circuit extending from the plus pole of battery, through the right-hand armature and back contact of relay 267, conductor 249, sequence switch contact 248', conductor 320, indicator contacts 319, 318, 317 and 316, indicator contact 321, conductor 322, a contact 30 35 251^a and the power magnet of sequence switch 203 to the minus pole of battery. Upon the deenergization of relay 207, the indicator 301 is arrested in the position predetermined by the sender. Upon the subsequent closure 40 of the fundamental circuit, the energizing circuit of relay 123 is closed at sequence switch contact 298', and contact 379 of indicator 301. When relay 207 becomes energized, indicator 302 is connected in circuit 45 through conductor 323, sequence switch contact 252 and conductor 224. This indicator controls in its contact 324 the actuation of the sender stepping relay. After the setting of indicator 302 and upon the deenergization 50 of relay 123, the plus battery applied through the right-hand armature and contact of relay 207 to conductor 320 is extended through indicator contact 325 and thence through the circuit traced in case of 55 indicator 300, including sequence switch contact 247, for moving sequence switch 203 out of position 6 and into position 7.

Upon the subsequent establishment of the fundamental circuit, the energizing circuit 60 of relay 123 is completed at sequence switch contact 294' and contact 380 of indicator 302, and thereupon the relay 207 connects plus battery through conductor 224, sequence switch contact 253, conductor 254, 65 and the power magnet of indicator 303 to

the minus pole of battery. This indicator controls at its contact 326 the actuation of the sender, and upon the deenergization of relay 207, following the setting of indicator 303, it will control at its contact 327 the closure of a circuit traced in case of indicator 301 and including sequence switch contact 251^a, for moving sequence switch 203 out of position 7 and into position 8.

On the subsequent closure of the fundamental circuit, the energizing circuit of relay 123 is closed at sequence switch contact 293' and contact 381 of indicator 303, whereupon the relay 207 connects plus battery through its left-hand armature, conductor 224 and contact 255, conductor 256, and the power magnet of indicator 304 to the minus pole of battery. Indicator 304 begins to operate and controls at its contact 328 the operation of the sender. When the upper zero counting relay again operates, the relays 112, 123 and 207 become deenergized. The indicator 304 is arrested and closes a circuit at its contact 329 in the same manner as indicator 302, through sequence switch contact 247, for moving sequence switch 203 out of position 8 and into position 9.

In position 9 of the sequence switch, as soon as the fundamental circuit is again closed, the energizing circuit of relay 123 is closed at sequence switch contact 294', and a contact 382 of indicator 304, whereupon relay 207 applies plus battery through its left-hand armature, conductor 224, sequence switch contact 257, conductor 258 and the power magnet of indicator 305 to the minus pole of battery. Indicator 305, during its operation, controls at its contact 330 the operation of the stepping relay.

Upon the last opening of the fundamental circuit by the upper zero counting relay, sender sequence switch contact 110 is closed, causing the movement of the sequence switch 100 out of position 11 and into position 16. Relays 112, 207 and 123 become deenergized.

After the setting of indicator 305 a circuit is closed from the plus pole of battery through the right-hand armature and back contact of relay 207, conductor 249, sequence switch contact 248', conductor 320, the contact 331 of the indicator 305, conductor 332, wiper 259, terminal 259', conductor 150, a contact 151 and the power magnet of sequence switch 113, to the minus pole of battery. This sequence switch is moved out of position 3 into position 4. A circuit is then closed from the minus pole of battery through sequence switch contacts 152 and 153, conductor 154, the winding of a relay 155, conductor 156, terminal 117, wiper 137, sequence switch contact 106, the secondary of a repeating coil 138, to the plus pole of battery. Relay 155 closes a circuit from ground through sequence switch contact 157, the contact and armature of relay 155, se- 130

quence switch contacts 158 and 159 and the winding of a relay 160 to the plus pole of battery. The relay 160 becomes energized and connects plus battery through its front contact and armature, conductor 163, terminal 295, wiper 294, conductor 228, sequence switch contacts 227 and 217, and the winding of relay 218 to the minus pole of battery. Relay 218 closes a circuit from 5 the plus pole of battery through its armature and front contact, conductor 215, conductor 260, a contact 261 and the power magnet of sequence switch 203 to the minus pole of battery, for causing the movement of this 10 sequence switch out of position 9 and into position 10. A circuit is now closed from the minus pole of battery, through sequence switch contact 262 and a lamp 263 to ground, lighting up this lamp. The lighting of this 15 lamp indicates the successful setting of all the indicators.

A circuit is also closed from the minus pole of battery through the winding of relay 207, conductor 206, sequence switch contacts 25 264 and 227, conductor 228, wiper 294, terminal 295, conductor 163, and then through the right-hand armature and front contact of relay 160 to the plus pole of battery. Relay 207 closes a circuit from the plus pole 30 of battery through its right-hand armature and contact, conductor 208, sequence switch contact 265, the armature and back contact of a relay 266 and the power magnet of allotter 202 to the minus pole of battery. 35 Assuming that this allotter is now in a position other than position 1, such as position 17, it will rotate until it reaches position 1. In this position the plus battery at relay 160 is connected, in the same manner as above described, to the conductor 206, and then through the left-hand armature and front contact of relay 207, conductor 224, sequence switch contact 266^a, conductor 40 267, a resistance 268, allotter contact 269 and the winding of the relay 266 to the minus pole of battery. Relay 266 becomes energized and opens in its back contact the driving circuit of allotter 202, thus causing the arresting of the allotter in position 1. 45 The plus battery at the right-hand armature of relay 207 is now connected through conductor 208, sequence switch contact 265, the armature and front contact of relay 266, allotter contact 270, a contact 271 and the 50 power magnet of sequence switch 203 to the minus pole of battery, for moving this sequence switch out of position 10 and into position 15. An allotter contact 272 is like a master contact and is closed in all positions except in the positions indicated adjacent such contact. While this contact is closed, relay 266 is short-circuited. For this reason it will be seen that the energization of relay 266, under the control of relay 55 207, is prevented, until the allotter 202 has

actually reached its stopping position indicated by numbers adjacent to contact 272, and thus the allotter cannot be arrested except when exactly stationed in these positions.

In a similar manner the allotter 202 may be caused to move, under the control of a relay similar to 207 individual to another trunk finder 201, into such positions as indicated adjacent to contact 272, the stopping circuit of the allotter being then controlled in its contacts shown above and to the left-hand side of contact 269. The allotter then, by closing the corresponding contact shown above contact 270, will cause 70 75 the movement of the sequence switch, associated with said other trunk finder, out of position 10 and into position 15.

Supposing that the sequence switch 203' is standing in position 10 and relay 207' is 80 energized. As soon as relay 266 becomes deenergized, a circuit is closed from the plus pole of battery, through the right-hand armature and front contact of relay 207', contact 265' of sequence switch 203', the armature and back contact of relay 266, and the power magnet of allotter 202 to grounded battery. The closure of this circuit would cause the allotter to move out of position 1, and to rotate until relay 266 85 becomes energized. In the present case, the circuit of relay 266 is completed in position 4 of allotter 202. The circuit extends from the minus pole of battery, through the winding of relay 266, allotter contact 269', 90 resistance 268', conductor 267', contact 266^b of sequence switch 203', the left-hand armature and front contact of relay 207', conductor 206', and then in the same manner as above described through the armature of 95 relay 160, or the armature of a similar relay associated with another trunk, to the plus pole of battery. In position 4 of allotter 202, a circuit would be closed from the minus pole of battery, through the power 100 magnet and contact 271' of sequence switch 203', contact 270' of allotter 202, the front contact and armature of relay 266, contact 265' of sequence switch 203', and the right-hand front contact and armature of relay 207' to the plus pole of battery. The sequence switch 203' would thus be moved 105 into position 15.

As it will be hereinafter set forth, in position 15 of a sequence switch like 203 or 110 203', the number of the called subscriber is displayed by means of lamp signals such as 348, in accordance with the set position of the number indicators. The set of lamps 348 is common to a plurality of indicators 115 like 300, and for this reason means are provided to prevent sequence switch 203' from moving into position 15 and thus cause the lighting of the lamps under the control of the indicator contacts shown within the 120 125 130

dotted rectangle in Fig. 3. This means consists in the provision of a circuit extending from the minus pole of battery, through the winding of relay 266, contact 269 of allotter 202 (which was moved into position 1 under the control of sequence switch 203), conductor 267, resistance 268, conductor 267, conductor 383, contact 384 of indicator 301, conductor 385, and contact 274' of sequence switch 203 to the plus pole of battery. Relay 266 is thus maintained energized while sequence switch 203 is in positions 14 to 17 (contact 274' being closed), and indicator 301 is in positions 0 to 4 (contact 384 being closed). While relay 266 is energized, sequence switch 203' cannot cause the allotter 202 to move out of position 1 into position 4, and for this reason allotter 202 cannot cause the sequence switch 203 to move out of position 10 and into position 15. In position 15, sequence switch 203' causes the movement of an indicator similar to 301, controlling contacts 340' and 341', in the same manner as sequence switch 203 controls the movement of indicator 301 into position 4. An indicator similar to 300 controls contacts 353', 351', 354', 350', 352', 356', and 355' in the same manner as indicator 300 controls contacts 353, 351, 354, 350, 352, 356 and 355. In view of the fact that, by means of another trunk finder similar to 201, the indicator controlling contacts 353', 351', etc., may be associated with a trunk selected by another selector like 116, this indicator may be operated simultaneously with indicator 300 to light up a certain number of the lamps of sets 348. Due to the provision of the above described arrangement whereby the sequence switch 203' is prevented from moving the indicator corresponding to 301 into position 4, this operation of the indicator corresponding to 300 is rendered temporarily ineffective.

The indicator 301 is used only for correcting the setting of indicators 300 and 302. This is necessary because the sender for controlling selector switches such as 113 used in this system, is arranged in accordance with a system of translation and may cause the sending of a different number of impulses than is represented by the numerical designation of the called subscriber's line. This arrangement of the indicators 300, 301 and 302 does not form a part of the present invention and will, therefore, not be fully explained herein. A detailed description of such an arrangement and an explanation of its purpose may be found in a copending application of A. E. Lundell, Serial No. 121,561, filed September 22, 1916, now Patent No. 1,260,412, Mar. 26, 1918, and a patent to A. E. Lundell, No. 1,232,944, July 10, 1917. Attention is only called to the peculiar numbering of the master con-

tact of indicator 302 and to the following 65 circuit arrangements:

If the indicator 300 has been moved under the control of the sender into any one of the positions indicated at its contact 333 and the indicator 301 into positions 2 to 3, then as 70 soon as the sequence switch 303 reaches position X, a circuit is closed from the minus pole of battery, through the power magnet of indicator 300, indicator contact 333, conductor 334, contact 335 of indicator 301, conductor 336, and sequence switch contact 273 to the plus pole of battery. Due to the closure of this circuit, the indicator 300 is caused to move into the next position, in which the contact 333 is open, that is to say, 80 if the indicator 300 has been caused to move into an even-numbered position and the indicator 301 into position 2, the indicator 300 will be moved into the next highest odd-numbered position. 85

If the indicator 301 has been moved into position 1, and the indicator 302 into one of the positions noted adjacent to its contact 337, then, as soon as the indicator 303 passes over position X, a circuit is closed from 90 grounded battery, through the power magnet and contact 337 of indicator 302, conductor 338, contact 339 of indicator 303, conductor 340', contact 341' of indicator 301, conductor 336, sequence switch contact 273 95 to the plus pole of battery. Due to the closure of this circuit, the indicator 302 will be moved into a resting position next to the position in which it was standing.

If the indicator 301 was moved into position 3, then both its contacts 335 and 341' are closed. For this reason, if the contact 333 of indicator 300 and the contact 337 of indicator 302 are closed, then the setting of both these indicators will be corrected. 100 105

After indicator 301 has corrected the setting of indicators 300 and 302, it is used for controlling the lighting of the lamps. As above described, upon the setting of the last indicator 305, the sequence switch 203 moves 110 under the control of an allotter 202 into position 15. It will be remembered that only one sequence switch like 203 can be in position 15 at a time. As soon as the sequence switch 203 passes through position 115 14, a circuit is closed from the plus pole of battery, through sequence switch contact 274, conductor 275, a contact 339 and the power magnet of indicator 301 to the minus pole of battery. In the present system, the indicator 301 is moved only to some position between zero and 3 for controlling the indicators. Due to the closure of the above traced circuit, the indicator 301 is moved into position 4. In its fourth position this 120 125 indicator closes the contacts shown above and below its contact springs 340, 341, 342, 343, 344, 345, 346 and 347. It will be noted

that contact springs 340 and 341 are arranged to connect ground to contacts controlled by indicator 300; contact springs 342 and 343 to connect ground to contacts controlled by indicator 302; contacts 344 and 345, to connect ground to contacts controlled by indicator 303; and contacts 346 and 347, to connect ground to contacts controlled by indicator 304. The contacts of indicator 300 are connected to a lamp set 348. In the same manner, the above mentioned contacts of each of the other indicators are connected to a lamp set similar to 348. The seven pairs of lamps of set 348 are permanently connected to the seven contacts of a plurality of indicators such as 300.

Due to the fact that the allotter 202 permits the movement of only one sequence switch like 203 out of position 10, into position 15, only one sequence switch like 203 can control the movement of its associated indicator 301 into position 4. For this reason only one translator 301 can be in position 4 at a time.

It will be noted that the seven pairs of lamps are connected in numerical order to the seven contacts of indicator 300 to which ground has been connected by the indicator 301. The lamps are arranged in an elliptical form around the lamps numbered 4. Supposing that the indicator 300 is standing in position zero, it will be seen that of its above mentioned seven contacts only contact 350, that is to say, the fourth contact, will be left open. For this reason all the lamps except the two lamps numbered 4 will be lighted. These lamps when lighted display the numeral zero. If the indicator 300 is standing in position 1, then of the above mentioned seven contacts only 351 and 352 are closed. Thus only the #3 and #6 lamps are lighted and display the numeral 1.

In position 2 of indicator 300, the contacts 353, 354, 350, 352 and 355 are closed, causing the lighting of the lamps numbered 1, 2, 3, 4, 5 and 7. These lamps when lighted display the numeral 2.

In position 3 of the indicator 300, contacts 353, 351, 350, 352 and 355 are closed. The lamps numbered 1, 3, 4, 6 and 7 will be lighted, causing the displaying of the numeral 3.

In position 4 of the indicator 300, contacts 351, 350, 352 and 356 are closed, causing the lighting of lamps numbered 2, 3, 4 and 6, causing the displaying of the numeral 4.

In the other positions of indicator 300, the mentioned seven contacts will be closed in an order which may be readily ascertained from the drawings, and will cause the displaying of a numeral corresponding to the resting position of the indicator.

The other indicators, controlled by means

of other contacts to which ground has been connected by indicator 301, cause the displaying of numerals in the same manner as described in connection with indicator 300.

The lamps controlled by springs 357, 358 and 359 of indicator 305, adjusted in accordance with the station designation of the desired party, are supplied with ground in position 15 of sequence switch 203, from sequence switch contacts 276 and conductors 360, and 361. The contacts of the indicator springs 357, 358 and 359 are wired to lamps adapted to display the letters R, J, M and W.

In position 15 of sequence switch 203 a circuit is closed from grounded battery, through a resistance 218, sequence switch contacts 214' and 213', and lamp 263 to ground. The lighting of this lamp, which has been extinguished when the sequence switch 203 moved out of position 11, indicates the successful operation of the indicator.

The "B" operator, having learned the number of the called station, inserts plug P into the desired multiple jack J and signals the station in the well known manner. In response to the insertion of the plug into the jack a sleeve relay 123^a becomes energized by current flowing through the sleeve contacts of the plug and jack, and closes a circuit through a sequence switch contact 125^a for moving the sequence switch 113 out of position 4 and into position 6.

When the sequence switch 113 opens its contacts 158 and 159, relay 160 becomes deenergized and opens the above traced locking circuit of relay 207. This latter mentioned relay closes then a circuit from the plus pole of battery, through its right-hand armature and back contact, the contact 226 and the power magnet of sequence switch 203 to the minus pole of battery, for driving the sequence switch out of position 15 and into position 16. A circuit is now closed from the plus pole of battery, through the right-hand armature and back contact of relay 207, conductor 249 and then this circuit divides into two branches, one branch leading through sequence switch contact 277, conductor 278 and the power magnet of indicator 300, to the minus pole of battery, and the other branch through sequence switch contact 279, conductor 280 and the power magnet of indicator 301, to the minus pole of battery. Due to the closure of this circuit, the switches 300 and 301 are returned to their normal position. The other indicators are returned to their normal positions by circuits extending from plus pole of battery, through sequence switch contact 281, conductor 360, a contact 361 and the power magnet of the indicator 302, to the minus pole of battery; from the plus pole of battery, through sequence switch contact 130

282, conductor 362, a contact 363 and the power magnet of indicator 303, to the minus pole of battery; from the plus pole of battery, through sequence switch contact 283, 5 conductor 364, a contact 365 and the power magnet of indicator 304, to the minus pole of battery; a circuit from the plus pole of battery, through sequence switch contact 284, conductor 366, a contact 367 and the 10 power magnet of the indicator 305, to the minus pole of battery.

When indicator 301 opens its contact 384, the relay 266 becomes deenergized, and the 15 sequence switch 203' is permitted to control the operation of allotter 202. When indicator 301 leaves position 4, the lamps are extinguished.

Upon the deenergization of relay 266, the 20 sequence switch 203' is permitted to operate in the above described manner. By causing the indicator corresponding to 301 to move into position 4, it will render effective the setting of the indicator corresponding to 300 by lighting the lamps 348.

25 A circuit is also closed from the plus pole of battery, through the sequence switch contact 285 and the winding of the magnet 286, to the minus pole of battery. Under the control of this magnet, the wipers of the 30 trunk finder 201 and the brush 220 are caused to travel in a downward direction. As soon as brush 220 reaches its normal position, a circuit is closed from the plus pole of battery, through brush 220, a conducting 35 plate 287, a contact 288 and the power magnet of sequence switch 203, to the minus pole of battery, for driving this sequence switch contact out of position 16 and into position 17.

40 As soon as all the indicators are released normally a circuit is closed from the minus pole of battery, through the power magnet of sequence switch 203, sequence switch contact 289, conductor 290, the normally closed contacts 368, 315^a, 316, 317, 318 and 319 45 of the indicators, conductor 320, sequence switch contact 248', conductor 249, and the back contact of armature 207 to the plus pole of battery. Due to the closure of this 50 circuit, the sequence switch 203 is moved out of position 17 and into position 18.

In position 18 of the sequence switch 203, the contact 204 is open, and therefore a sequence switch like 113 when it moves into 55 position 2 and closes its contact 127 cannot cause the energization of relay 207 and thus operate the trunk finder 201 to associate the indicators shown in Fig. 3 with the trunk seized by the selector 116. The sequence 60 switch 203 will remain in position 18 until it is preselected for service by the allotter 200. This will occur when in position 17 of the allotter, a sequence switch similar to 65 203 reaches position 4 and closes its contacts corresponding to contacts 237 and 238 of

sequence switch 203, for causing the movement of the allotter out of position 17 into position 1. As soon as the allotter reaches position 1, a circuit is closed from ground, through its contact 236, the contact 237 and 70 the power magnet of sequence switch 203 to grounded battery, for moving this sequence switch out of position 18 into position 1.

The apparatus shown in Figs. 2 and 3 is now again ready for service. 75

The sequence switch 113 will be driven out of position 16 and back into its normal position, in response to the completion of the connection between the calling and called subscribers, in accordance with the number 80 displayed by the lamps, and in response to the restoration of this connection. The circuits for controlling such operation of the sequence switch are not disclosed in the present application, because they do not form a 85 part of the invention claimed hereinafter.

What is claimed is:

1. In combination, a plurality of telephone lines, a plurality of senders, means for associating any one of said senders with 90 any one of said lines, a plurality of selectively operable switches arranged to operate under the control of any one of said senders, a finder for each of said switches arranged to connect the associated switch to 95 any one of said lines, means operative upon the connection of a sender to a line for operating one of said finders to connect with said last mentioned line, a variably operable signal, means controlled by any one of 100 said switches for operating said signal, and means for permitting the successful operation of said signal by only one switch at a time.

2. In combination, a signal, a plurality 105 of switches, independent controlling devices for setting each of said switches into a certain position, a contact for each of said switches operable when the respective switch is in said certain position for actuating said 110 signal, and means for determining the succession in which said contacts should be actuated.

3. In combination, an electric signal, two contacts, each arranged to actuate said signal, two controlling switches, one provided for each contact, and means for determining the succession in which the actuation of 115 said contacts should become effective.

4. In combination, an electric signal, two 120 actuating circuits for said signal, two contacts in each of said circuits, means for actuating one of the contacts in both circuits, and means operative thereupon for determining the succession in which the second 125 contacts should be actuated.

5. In combination, an electric signal, two actuating circuits for said signal, a pair of switching devices for controlling each of said circuits, means controllable at a distant 130

point for operating one pair of switching devices, other means controllable at a distant point for operating the other pair of said devices, and a common means for coöperating in the control of one switching device in each pair.

6. In combination, an electric signal, two actuating circuits therefor, a pair of switching devices for controlling each of said circuits, means controllable at a distant point for operating one pair of switching devices, other means controllable at a distant point for operating the other pair of said devices, an allotter coöperating in the control of one switching device in each pair, and means controlled by said allotter for temporarily preventing the operation of the switching device the pair of which was the last to be started.

7. In combination, an electric signal, two actuating circuits therefor, a pair of switching devices for controlling each of said circuits, means controllable at a distant point for operating one pair of switching devices, other means controllable at a distant point for operating the other pair of said devices, an allotter having two operating positions, means actuated upon the association of said one pair of switching devices with said means at a distant point for moving said allotter into the first operating position, means actuated in response thereto for completing the operation of said one pair of switching devices, automatic means for releasing said last mentioned devices, means operative upon the association of the second pair of devices with said other means at a distant point for moving said allotter into its second operating position, means actuated in response thereto for completing the operation of said second pair of devices, and means operative until the release of a switching device of said one pair is started for maintaining said allotter in its first operating position.

8. In combination, a plurality of telephone lines, a plurality of senders, selectively operable means for associating any one of said senders with any one of said lines, an electric signal, two actuating circuits therefor, a pair of switching devices for controlling each of said circuits, said devices being adjustable under the control of any one of said senders, a finder for each pair of switching devices arranged to seize any one of said lines, mechanism for successively preselecting said finders for service, means operative upon the connection of a sender to a line for operating a preselected finder to seize said line, means operative thereupon for actuating said mechanism to preselect another finder for service, an allotter having two operating positions, means actuated upon the association of one pair of switching de-

vices with a sender for moving said allotter into the first operating position, means actuated in response thereto for completing the operation of said one pair of switching devices, automatic means for releasing said last mentioned devices, means operable upon the association of the second pair of devices with a sender for moving said allotter into its second operating position, means actuated in response thereto for completing the operation of said second pair of devices, and means operative until the release of a switching device of said one pair is started for maintaining said allotter in its first operating position.

9. In combination, a signal, a plurality of switches arranged to actuate the same, an allotter having a plurality of positions and controlling in its various positions the operation of said switches, means controlled by any one of said switches for moving said allotter into a position permitting the operation of the controlling switch, and means operative thereupon for preventing the other switches from actuating said allotter until said controlling switch successfully completes its operation.

10. In combination, a signal, a plurality of selectively operable switching devices each arranged to control said signal, separate means controllable at a distant point for operating said devices, a sequence switch for each of said devices arranged to co-operate in their control, an allotter having a plurality of operating positions, means under the joint control of any one of said sequence switches and said allotter for causing one of said devices to actuate said signal, and means controlled by said actuated device for preventing the mentioned coöperation of another of said sequence switches and said allotter.

11. In combination, a signal, two switches each arranged to actuate said signal, an allotter having a plurality of positions, means controlled by the first switch for moving said allotter into a certain position, means operative thereupon for actuating said first switch to actuate said signal, means controlled by the second switch for moving the allotter into another position, means operative thereupon for causing said second switch to operate said signal, and means for preventing said second switch from operating said allotter until said signal has been successfully actuated by said first switch.

12. In combination, a signal, a plurality of switches arranged to control the actuation of the same, an allotter having a plurality of positions and controlling in its various positions the operation of said switches, a circuit for said allotter having a common portion and a plurality of branches, a contact in each of said branches, each con-

tact being operable by another one of said switches, means operable upon the actuation of any one of said contacts for moving said allotter into a position permitting the successful operation of the switch actuating the contact, a relay controlling the common portion of said circuit, and means for actuating said relay while a switch is successfully operated.

10 13. In combination, a signal, a plurality of selectively operable switching devices each arranged to control said signal, a plurality of senders, means for associating any one of said senders with any one of said 15 switching devices, a sequence switch for each of said switching devices, an allotter having a plurality of operating positions, a circuit for said allotter having a normally closed common portion and one branch for 20 each of the sequence switches, a normally

open sequence switch contact in each of said branches, means operable upon the successful adjustment of a selectively operable switching device for operating the associated sequence switch to actuate its normally open contact, means operative thereupon for moving said allotter into a certain operating position, means operative in said position of the allotter for permitting the successful operation of the adjusted switching device, a relay controlling the common portion of said circuit, and a circuit for said relay jointly controlled by any one of said sequence switches and any one of said signals.

25 In witness whereof I hereunto subscribe my name this 31st day of October, A. D. 1917.

30 35 FRANK N. REEVES.
